(57) **CLAIM**

The ornamental design for a smart speaker set, as shown and described.

DESCRIPTION

FIG. 1 is a front view showing an embodiment of a smart speaker for the smart speaker set;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front view showing an embodiment of a stand for the smart speaker set;

FIG. 8 is a rear view thereof;

FIG. 9 is a left-side view thereof;

FIG. 10 is a right-side view thereof;

FIG. 11 is a top view thereof;

FIG. 12 is a bottom view thereof;

FIG. 13 is a front-right perspective view thereof;

FIG. 14 is a rear-left perspective view thereof;

FIG. 15 is a front view showing an embodiment of the smart speaker set;

FIG. 16 is a rear view thereof;

FIG. 17 is a left-side view thereof;

FIG. 18 is a right-side view thereof;

FIG. 19 is a top view thereof;

FIG. 20 is a bottom view thereof;

FIG. 21 is a front-right perspective view thereof; and,

FIG. 22 is a rear-left perspective view thereof.

The broken lines in FIGS. 1-22 illustrate portions of the smart speaker set that are not part of the claimed design.
